Primary Examiner — Lauren D McVey

Assistant Examiner — Elisa M Pujals

(57) **CLAIM**

The ornamental design for a toy, as shown and described.

DESCRIPTION

1. Toy
2. Toy
- 1.1 is a top perspective view of a first embodiment of a toy, showing our new design;
- 1.2 is a bottom perspective view thereof;
- 1.3 is a front elevation view thereof;
- 1.4 is a rear elevation view thereof;
- 1.5 is a left-side elevation view thereof;
- 1.6 is a right-side elevation view thereof;
- 1.7 is a top plan view thereof;
- 1.8 is a bottom plan view thereof; and
- 1.9 is an exploded front and top perspective view thereof.
- 2.1 is a top perspective view of a second embodiment of a toy, showing our new design;
- 2.2 is a bottom perspective view thereof;
- 2.3 is a front elevation view thereof;
- 2.4 is a rear elevation view thereof;
- 2.5 is a left-side elevation view thereof;
- 2.6 is a right-side elevation view thereof;
- 2.7 is a top plan view thereof;
- 2.8 is a bottom plan view thereof; and
- 2.9 is an exploded front and top perspective view thereof.

1 Claim, 18 Drawing Sheets
